CABINET FOR HOUSING APPARATUS PERMITTING THE TRANSMISSION AND RECEPTION OF WRITTEN MATERIAL BY TELEPHONE

James L. Rodgers, Tempe, and Joseph L. Tyrrell,
Phoenix, Ariz., assignors to Talos Systems, Inc.,

Filed Oct. 18, 1971, Ser. No. 190,434

Term of patent 14 years

Int. Cl. D14—03

U.S. Cl. D26—14 R

FIG. 1 is a perspective view of a cabinet for housing apparatus permitting the transmission and reception of written material by telephone showing our new design;

FIG. 2 is a top, plan view of the cabinet;

FIG. 3 is a view of the rearmost end of the cabinet, and;

FIG. 4 is a side view of our cabinet.

We claim:

The ornamental design for cabinet for housing apparatus permitting the transmission and reception of written material by telephone, as shown.
